Patented Mar. 30, 1965

200,740

FRONT PANEL FOR AN AIR CONDITIONER

Carl W. Sundberg, Bloomfield Hills, and Richard A. Heck,
Southfield, Mich., assignors to Whirlpool Corporation,
a corporation of Delaware

Filed Oct. 18, 1963, Ser. No. 77,027

Term of patent 14 years

(Cl. D62—4)

FIG. 1

FIG. 2

FIG. 3

FIGURE 1 is a front elevational view of a front panel for an air conditioner, showing our new design.

FIGURE 2 is a side elevational view thereof; and

FIGURE 3 is a perspective view thereof.

The dominant features of our design reside in those portions shown in full lines.

We claim:

The ornamental design for a front panel for an air conditioner, substantially as shown.
